REFLEX MEASUREMENT APPARATUS

Stephens N. Sato, San Diego, Calif., assignor to
Ivac Corporation, San Diego, Calif.

Filed Apr. 14, 1970, Ser. No. 22,423

Term of patent 14 years

Int. Cl. D24—02; D10—08

U.S. Cl. D83—1

FIG. 1 is a perspective view of a reflex measurement apparatus embodying my new design;

FIG. 2 is a left side elevational view of the reflex measurement apparatus shown in FIG. 1;

FIG. 3 is a top plan view of the reflex measurement apparatus shown in FIG. 2; and

FIG. 4 is a rear elevational view of the reflex measurement apparatus shown in FIG. 1.

I claim:

The ornamental design for a reflex measurement apparatus, as shown.
